UNITED STATES PATENT OFFICE.

OTTO A. FEEDERICKSON, OF WETHERSFIELD, CONNECTICUT, ASSIGNOR TO THE AMERICAN WIREMOLD COMPANY, OF HARTFORD, CONNECTICUT, A CORPORATION OF CONNECTICUT.

BRAIDING MACHINE.

Application filed May 1, 1928. Serial No. 635,932.

To all whom it may concern:

Be it known that I, Otto A. Feederickson, a citizen of the United States, residing at Wethersfield, in the county of Hartford, and State of Connecticut, have invented an Improvement in Braiding Machines, of which the following description, in connection with the accompanying drawings, is a specification, like characters on the drawings representing like parts.

This invention relates to braiding machines, and more particularly to braiding machines of that type wherein the braiding filaments are supplied from two series of holders which are moved in a circular path in opposite directions about the braiding point.

One of the main objects of the present invention is to provide a braiding machine of the above general type which may be operated at high speed to thereby facilitate production and economy of output. Many factors and features of construction have heretofore limited the speed at which a braiding machine may be safely operated, and the present invention in its broader aspects relates to a reorganization in coordination of the various parts to the end that a braiding machine may be provided that may be run at relatively high speed and at the same time be free from the uncertainties of operation heretofore present in such machines when run at speed.

In a braiding machine where the filaments to be braided have been supplied from inner and outer filament holders revolving in opposite directions about the central braiding point, much uncertainty of operation has been introduced by failure to give due consideration to the passage of the outer filaments about the inner filament holders, and frequently the outer filament has been broken or so far injured by frictional engagement with mechanical parts that defective product has resulted. One of the important features of the present invention, therefore, consists in a braiding machine wherein the peripheral or surface speed of the inner filament carrier drivers is made substantially the same as the movement of translation imparted to the outer filaments, so that all danger of breaking or injuring the outer filaments as they pass around the inner filament carriers is avoided.

In a high speed braider, practice has

shown that the inner filament carriers must travel in their annular path about the braiding point in substantially a horizontal plane and that the filament from the inner filament carriers should be drawn from the filament holders in a direction at right angles to the axes of rotation of such holders, and delivered from the carriers towards the braiding point in substantially the longitudinal axes of the inner filament holders.

One of the features that has heretofore contributed largely to limitation in speed of the braiding machine has been the lack of stability of the main rotary frame carrying the outer filaments, and the parts associated therewith. Heretofore it has been proposed to provide ball bearings to support the relatively movable parts, but these have usually been so disposed that while they have served to reduce friction between the parts, they have failed to stabilize the movement of the parts and prevent chatter under high speed. In this connection the present invention provides roller race ways so disposed with relation to each other and the parts which they support that the main rotary frame, the driver frame, and associated elements are stabilized in their relative movements and rendered firm in their supporting relation with the main supporting frame.

The various features referred to hereinbefore in a general way aim to give to the braiding machine a capacity for high speed as compared with braiding machines heretofore in practical use, and the novel features hereinbefore referred to, as well as others that will be hereinafter described, will best be made clear from the following description and the accompanying drawings of one good practical form of a braiding machine containing the present invention.

In the drawings:

Fig. 1 is a perspective view of a braiding machine containing the features of the present invention;

Fig. 2 is a cross-sectional view of the braiding machine taken through the driving element;

Fig. 3 is an enlarged detail in plan view showing more particularly a portion of the rotary main frame, one of the inner carriers, and the relation of these parts to the stopping and starting mechanism;

Fig. 4 is an enlarged detached detail showing portions of the main rotary frame,

the outer filament supplies, and a novel means for withdrawing the filament from the supplies and shifting it about the inner carriers;

5 Fig. 5 is a detail in horizontal section of one form of trip mechanism for automatically stopping the machine when one of the outer or inner filaments breaks, or at the pleasure of the machine attendant; and

10 Fig. 6 is an enlarged perspective view of one of the inner filament carriers showing the details of the construction thereof and a novel form of driver mechanism.

15 The product of the braiding machine in accordance with the present invention may be a braided strand, a braided tube, or a braided covering for a core, and in the following description this capacity of the machine will be understood. The character of 20 the filaments that may be braided may vary within wide limits and be constituted as yarns, strands, silk, wire, and in fact any usual type of filament adapted for the general purposes of braiding, but hereinafter, 25 for the sake of brevity and identification, the term "yarn" will be employed in its broad sense to designate all of these different kinds of filaments.

30 The supporting frame for the operating parts of the machine may be of any suitable type in which rigidity and freedom from vibration is generally desirable. In the present case the supporting frame comprises the table or top plate 1 mounted upon suitable legs 2 and rising from the top frame or table 1 is the fixed can plate 3.

35 The supporting frame carries a yoke 4 which at its central lower portion is provided with a fixed bearing 5 for the upwardly extending fixed central tube 6, the construction being such that the yoke frame and central bearing 6 form rigid supports for certain of the moving parts of the machine, as will presently appear.

40 The central support 6 is formed as a hollow tube, and in the present instance there is shown a core 7, which is passed through the central support 6 and is to be covered with the braiding material at the braiding point.

45 The table 1 is of circular contour, as indicated in Fig. 1, and has the arched frame 8 secured to it at opposite sides of the vertical central axis of the machine. Secured 50 to the arch 8 is the arm 9 extending towards the axis of the machine and at its inner end supporting the sleeve or tubular conduit 10, the lower end portion of which is preferably tapered and constitutes what may be hereinafter termed the "braiding point" 11. The conduit 10 is formed tubular as shown and the core, in the present instance, as it is covered by the braiding material, passes upwardly, as indicated in Fig. 1, and about the take-up drum 12. The take-up drum 12

is mounted on the shaft or spindle 13 carried by a frame 14 which may be conveniently formed as a part of the arch 8 or be secured thereto. The take-up drum 12 is connected to or is formed with the take-up gear 15, 70 Fig. 1, and is driven from a similar gear 16 through a train of mechanism which, in the present instance, is shown as a shaft 17 having a pinion 18 meshing with a gear 19 carried by the supporting frame 14 and an 75 extension from the side thereof, as indicated in Fig. 1.

The gear 19 is fixed to the shaft 20 on which is the beveled gear 21 driven by a correspondingly beveled gear 22 on the upright shaft 23, the lower end portion of which may be connected by suitable means to a going part of the machine, the construction being such that as the machine is operated to braid the yarn, the finished product is taken up by the take-up mechanism. 85

80 Mounted for rotative movement upon the central support 6 is a sleeve 24 to which is secured the driver gear 25. The driver gear 25 is connected to the drivers, as will more fully appear, to impart thereto a movement to traverse the inner yarn carriers in their annular path. 90

85 Loosely mounted upon the sleeve 24 is the hub 25* of the main rotary frame 26 which is of general circular contour having the upwardly extending outer portions 27.

90 The main rotary frame 26 carries the toothed circular rack 28 on its under surface and the driver gear 25 carries a similar toothed rack 29, both of which are engaged by a driving gear 30, Fig. 2, and may be driven in opposite directions by rotation of 100 said gear. 105

95 The toothed racks 28 and 29 are of large diameter and are preferably secured to the main rotary frame and the driver gear at a point remote from the machine center in order to contribute to stability and ease in 110 running at high speed.

105 The driving gear 30 is mounted on the shaft 31, Fig. 2, which is supported in suitable bearings 32 carried by the machine supporting frame. In the present instance the bearings 32 are formed in the yoke frame 33 which may be hung from the table or top frame 1. 115

110 Mounted upon the driving shaft 31 are the fixed and loose pulleys 34 and 35 respectively which are adapted to be engaged by a driving belt 36 actuated from a suitable source of power, not shown. In order that the belt may be conveniently shifted from one to the other of said pulleys to permit the machine to be either run or remain at rest, a belt shifter 37 is provided, between the bifurcated end portions of which runs the belt 36, Fig. 1. The belt shifter 37 is secured to the upwardly extending shaft 38, 125 130

Fig. 1, which is normally under the influence of a spring 39 tending to move the belt shifter in a direction to shift the belt from the fast to the loose pulley. The upper end of the shaft 38 is also provided with a hand operated lever 40 for throwing the belt shifter by hand when desired.

The lever 40 is provided with a catch for holding the belt shifter in machine operating position. In the present instance the catch is formed by an arm 41 pivoted at 42 to the lever 40 and having a shouldered end portion 43, best shown by Fig. 5, which is automatically thrown into engagement with a trip 44 when the lever is moved to start the machine.

The trip 44 will maintain the belt upon the fixed pulley and so long as the parts remain in the described position the machine will continue to run, when, however, the trip 44 is pulled from its holding position with the arm 41, Fig. 5, as may be done by any usual form of electro-magnet and armature mechanism, the machine will be automatically brought to rest.

To stabilize the machine so that it may be run smoothly and evenly at high speed, the driver gear 25 and the main rotary frame 26 are each supported by associate driver gear 25 has its under surface recessed at 47 near the periphery of the driver gear to receive the anti-friction balls 46. Above the lower ball race 45 is the upper ball race 48 which is supported from the driver gear, and anti-friction balls 49 are interposed between the upper ball race 48 and the under recessed surface of the main rotary frame 26. In the present instance, the upper ball race 48, which is constituted as a ring of the same radius as the lower ball race, is supported by the risers 50 secured to and extending upwardly from the driver gear, so that the upper ball race 48 rotates with the driver gear in the same circular arc as the raceway in the lower ball race. It has been common heretofore to provide anti-friction balls between the opposite revolving members in a braiding or circular machine, but in the present instance the upper and lower ball races are mounted at points remote from the axes of rotation of the parts supported by them and are of novel construction, the result being that all up and down or chattering movement of the main rotary frame and associated connections

is avoided and the machine may be run smoothly at high speed.

The upwardly extending portion 27 of the main rotary frame is provided with an annular trackway 51, as indicated in Figs. 3 and 4, in which run the elongated shoes 52 of the inner yarn carriers. The elongated shoes 52 of the inner yarn carriers form an important feature of the construction, because under the centrifugal action at high speed the elongated shoe bearings 52 enable the carriers to move in their annular path with a smooth and uniform movement. This feature of the construction, however, is not claimed in this application, because it constitutes the subject matter of the O. A. Frederickson Patent No. 1,501,846, granted July 15, 1924.

The inner yarn carriers, in accordance with the present invention, are novel in construction and are formed by the side frames 53, Fig. 6, which extend inwardly from the shoes 52 and are connected at their inner ends by the cross-frame 54 carrying a roller 55 which rests upon a trackway 56 which may be conveniently supported in fixed position, as will later appear. Thus the inner yarn carriers are supported at their outer portions in the annular trackway of the main rotary frame by the shoes 52, while the inner end portions of the carriers extend horizontally towards the braiding point and are supported by a roller and track.

Where the machine is run at high speed it is desirable that the yarn shall be delivered from the inner yarn carriers from a point in longitudinal extension of the yarn carrier and towards the braiding point. In accordance with the present invention the yarn carriers are adapted for the support of the wound yarn on an axis extending radially of the circular path of movement of the carriers, and the yarn is unwound from the yarn mass in each carrier by the pull of the yarn at substantially right angles to the axis of rotation of the yarn mass. In the present instance, as indicated in Figs. 3 and 6, each inner yarn carrier is provided with a bail 57 under which the inner yarn *a* is passed from the inner yarn mass within the carrier. From the bail 57 the yarn is passed transversely above the yarn mass over a vail 58 at the opposite side of the carrier, then through the guide eye 59 at that side of the carrier, then outwardly to the tension device 60 which may be conveniently formed as two friction disks. From the friction disks or tension device 60 the yarn *a* passes inwardly of the carrier about an inner guide 61, for the support of which each carrier has an inner guide support or extension 62 formed thereon, the construction being such that the inner guide 61 directs the yarn to the braiding point substan-

tially in longitudinal extension of the yarn mass within the carrier.

The bearings 63 for the support of the yarn mass within the carriers may be of usual construction, as indicated in Fig. 6.

Each inner yarn carrier is provided with guides 64, 65, one of which extends above and the other below the carrier for guiding the outer yarn from contacting engagement with the carrier as the two are moved in opposite directions.

It has been the common practice heretofore to traverse the inner yarn carriers by means of drivers which have been frictionally driven in some cases, and in others have been positively driven. In all these cases, however, the outer yarn from the outer yarn supplies has been passed between the engaging surfaces of the driver and a co-acting part on the carrier, with the result that the yarn has often been broken. In accordance with the present invention, however, especially where the machine is driven at high speed, it is desirable that the drivers be driven positively at a peripheral speed equal to the movement of translation imparted to the outer yarn by the revolution of the main rotary frame, because under such condition all liability of injuring the yarn or breaking it as it passes between the driver and the driver engaging element on the carrier is avoided. As further contributing to non-injurious influence upon the outer yarn as it is shifted past the yarn carriers, the present invention provides a novel driver which is positively driven and cooperates with a novel form of rotary member on the carrier to be driven.

Secured to the sleeve 24, hereinbefore described as carrying the driver gear 25, is the driver frame 66 which may be preferably formed by spider arms extending outwardly from the hub portion 67, as best shown in Fig. 2. Each of the radially extending spider arms 67 is provided with a bearing 68 at its outer end in which is mounted the short shaft 69, the inner end portion of which carries a beveled gear 70 which engages a fixed or stationary toothed rack 71 carried by a frame 72, the hub portion 73 of which is secured to the central stationary tube 6, as indicated in Fig. 2.

Secured to each of the short shafts 69, Fig. 6, is the driver 73 which, as illustrated in Fig. 6, is formed with a series of radially extending teeth 74 tapering outwardly and preferably formed of some non-abrasive material such as fibroid or the like. The outwardly tapering teeth 74 provide between them the spaces 75 in which the outer yarn *b* may rest as it passes between the carrier and its driver. The teeth 74 of the driver have rounded outer end portions 76 on which the outer yarn *b* will not hang but from which it will slip and enter the yarn

protecting opening 75 between the teeth as the outer yarn is passed between the carrier and driver.

The toothed driver 73 may be variously contrived but it has been found in practice that a good form of such driver consists in a toothed disk formed of fibroid or like material and secured to the short shaft 69 by means of an overlying plate 77 which may be clamped upon the face of the disk by a set nut 78, Fig. 6. The drivers 73, it will be understood, occupy a position slightly to one side of the rollers 79, so that when the drivers are advanced in a circular path by the driver frame 66 they push the inner carriers around, and at the same time the drivers are positively rotated by the pinions 70.

Each inner yarn carrier is provided with a roll or roller for cooperation with the driver, as shown in Fig. 6, and the present invention contemplates that such roll or roller 79 shall be mounted for rotation in the opening 80 formed in the shoe 52 and that the peripheral portion of the roller 79 may be fluted or provided with indentations and rising portions of less depth than the teeth 74 of the driver. In the present instance the roller 79 is provided with the flutes 81 alternating with depressions 82 which are engaged by the end portions of the teeth 74 of the drivers as the carrier is moved in its annular path.

As is usual in the type of braiding machine to which the present invention relates, the main rotary frame has mounted thereon a series of yarn masses which are carried around the central axis of the machine in one direction while the inner yarn masses supported by the carriers are moved around the same point in the opposite direction, and means are usually provided in such type of machine for shifting the outer yarn so that it will pass over one carrier and under another as the main rotary frame and carriers move in their respective paths. In a braiding machine which is designed to run at high speed it is essential that the outer yarn shall be led to the braiding point and shifted with respect to the carriers and maintained under proper tension during the braiding operation.

In accordance with the present invention, the upwardly extending flange 27 of the main rotary frame 26 supports a metal or brass ring 83, Figs. 2 and 4, which is insulated from the main rotary frame by insulated material 84, and this ring has a downwardly extending annular flange which is spaced inwardly from the annular wall 27. Rising from the metal or brass plate 83 are the supports 85 for the outer yarn supplies 86, and the yarn from such outer yarn supplies is shifted relative to the inner carriers by a shifting mechanism which, in the pres-

ent instance, is of novel character. Pivotally mounted at 87 on the main rotary frame is the shifter arm 88, one of said arms being supplied for each outer yarn mass. The shifter arm 88 has a yarn guiding portion or slot 89 at one end, which directs the outer yarn *b* through the wide slot 90 extending through the flange portion 27 of the main rotary frame. The shifter 88 carries a pin 91 on which is mounted a shoe 92 which travels in the shifter cam 93 formed in the fixed upwardly extending flange 3 of the table or support 1, the construction being such that as the main rotary frame is revolved about the machine center, the shoe 92 at one side of the pivotal mounting of the shifter will cause the shifter to move the arm upwardly or downwardly and deliver it in proper position for passing the outer yarn over or under the inner yarn carrier.

In a high speed braider of the present type it is desirable that proper tension be maintained upon the outer yarn as it is delivered to the braiding point and that it be shifted with a smooth, uniform motion as contradistinguished to the quick snappy action usually found in practically all machines now in use. The present invention, therefore, contemplates that the end portion of the shifter arm which carries the yarn guide 89 be formed of springy material so that the arm may flex inwardly toward the center of the braiding machine as the tension of the yarn increases and will spring outwardly as the tension of the yarn decreases. It is also desirable to make the part of the shifter arm on the opposite side of the pivotal support relatively heavy as at 94, Fig. 4, to balance the weight of the end portion having the yarn guide 89.

To insure a smooth action and proper presentation of the outer yarn *b* by the shifters, the upwardly extending portion 27 of the main rotary frame is provided with bearings 95 and 96, one at each side of the pivotal support 87 of the shifter arms and against which the adjacent parts of the shifter arms may bear as they are moved to shift the outer yarn. If desired, the bearing 96 adjacent the end of the shifter arm carrying the yarn guide may be curved to effect slight movement of the yarn guide portion of the shifter arm to compensate for the difference in distance between the braiding point and said yarn guide when the shifter takes its different positions.

The yarn from the outer yarn masses or supplies 86 passes about a rod or bail 97, Fig. 4, and the pull of the yarn is at right angles to the axis of rotation of the outer yarn masses or supplies. From the rod or bail 97 the yarn passes through the guide eye 98 and then through the yarn tension device 99 which may be constituted as disks yieldingly held towards each other by a

spring 100, Fig. 4. From the tension device 99 the outer yarn passes about a roller 101 mounted at the pivotal axis of the shifter arm, Fig. 4, so that as the shifter arm oscillates, the yarn is presented from its guiding end in a smooth, uniform manner, and under uniform tension to the braiding point.

It is usual in braiding machines to provide some kind of automatic stop mechanism to stop the machine when one of the yarns breaks. The present machine is provided with such a mechanism in which there are novel features, and further, with stopping mechanism which may be actuated by the attendant from different portions of the machine.

In the invention, as shown, the stopping mechanism is of the electro-magnetic type and comprises a source of electrical energy or battery 102, Fig. 2, one pole of which is connected by a conductor 103 to a plate 104 mounted upon an insulated material, on the bearing 5 of the machine frame. The plate 104 has mounted in its a plunger 105 normally under the influence of a spring 106 which projects the plunger 105 upwardly against the under exposed surface of the contact plate 107 secured beneath the hub portion 108 of the driver gear. The plate 107 is insulated from the driver gear and is connected electrically to the plunger 109 normally pressed upwardly against the exposed under surface of a contact plate 110 on the hub 25* of the main rotary frame 26, by a spring 111. The insulated contact plate 110 is connected by an insulated conductor 112, Fig. 2, with the metal or brass plate 83.

The other pole of the battery or source of electrical energy is connected to the post 113, Figs. 2 and 3, where it is grounded.

Each of the inner yarn carriers is provided with a sliding contact 114 pivotally mounted on the carrier at 115, Fig. 6, a spring 116 normally acting to hold the contact 114 in sliding engagement with the metallic or brass ring 83. The contact 114 is connected by an insulated conductor 117 to a post or contact 118 mounted at the inner end portion of each carrier. Supported for sliding movement in a lug 119, mounted upon the inner end of each carrier is a spring pressed plunger 120 having a hooked end 121 to engage the yarn *a* extending inwardly from the guide 61 towards the braiding point. The tension of the yarn which is engaged by the hook 121 is sufficient to hold the contacts 118 and 120 out of engagement against the tension of the spring 122, Fig. 6. When, however, the yarn on one of the carriers breaks or becomes too slack for braiding purposes, the contact 120 is released, the circuit completed and the armature 123, Fig. 5, is energized, thereby re-

leasing the trip 44 from engagement with the catch 41 and permitting the belt to be shifted from the fast to the loose pulley under the impulse of the spring 39 and the machine to stop.

In order to stop the machine in case of the breakage of one of the outer yarns, the outer yarn *b* passes over the hooked end portion 126 of a contact member 127 mounted on the upwardly extending flange portion 27 of the main rotary frame, such contacts being normally impelled upwardly by the springs 128. When one of the outer yarns breaks, the plunger or contact 127 is released and engages the under surface of the metallic or brass ring 83 and completes the circuit to effect machine stoppage.

It is convenient to enable the machine attendant to stop the machine from different portions thereof, and to this end one or more push buttons 124 may be located at different parts of the machine and connected to the electric circuit. Associated with each push button is a ground 125, whereby upon contact of the push button and ground wire, the circuit is completed, the armature energized and the machine stopped.

In machines of the general type described, the length and diameter of the yarn masses carried by the carriers are limited by the size of the machine, the throw of the cams, and the size of the carriers themselves, a condition which does not obtain with respect to the outer yarn supplies. The yarns for these machines are commonly wound upon paper cores and are furnished in standard sizes, usually too large to place within the inner carriers of a braiding machine, the result of which is that this yarn has to be rewound, at least before it is placed in the inner carriers. In the O. A. Frederickson Patent No. 1,490,260, granted April 15, 1924, a method of obviating these difficulties, cheapening manufacture, and supplying yarn masses of the standard size to the machine is described and claimed, and while the present machine which forms the subject of this invention proposes to employ the method hereinabove mentioned in facilitating economy of production, such method is not herein claimed as it forms the subject of the said prior application.

What is claimed is:

Claims.

1. In a high speed braiding machine, the combination of a main rotary frame supporting outer yarn supplies and having slots through which the outer yarns pass inwardly toward the braiding point and an annular groove, horizontally disposed inner yarn carriers having shoes projecting from their outer ends into said groove to form a sliding support for the outer ends of the carriers, a fixed annular frame positioned below the carriers to support their inner ends and pro-

vided with an annular rack, rollers at the inner ends of the carriers that run upon said annular frame, a series of drivers for traversing the inner carriers and having tapered notches thru which the yarn may travel freely, a driver frame for advancing the drivers and provided with pinions connected to the drivers and meshing with said rack positively to rotate the drivers at a peripheral speed equal to the movement of translation of the outer yarn supplies relative to the inner carriers, and means for rotating said main frame.

2. In a high speed braiding machine, the combination of a main rotary frame supporting outer yarn supplies and having slots thru which the outer yarns pass toward the braiding point and an annular groove, horizontally disposed inner yarn carriers having projections at their outer ends that extend into said groove to support the outer ends of the carriers, a fixed annular frame positioned below the carriers to support their inner ends and provided with an annular rack, a series of toothed drivers for traversing the inner carriers and having deep yarn receiving notches between the teeth for the free passage of the yarn, a driver frame for advancing the drivers and provided with pinions connected to the drivers and meshing with said rack positively to rotate the drivers at a peripheral speed equal to the movement of translation of the outer yarn supplies relative to the inner carriers, and means for rotating said main frame.

3. In a high speed braiding machine, the combination of a main rotary frame supporting outer yarn supplies and having an annular wall in which an annular groove is formed, horizontally disposed inner yarn carriers having projections at their outer ends that extend into said groove to support the outer ends of the carriers, means for supporting the inner ends of the carriers, a series of toothed drivers for traversing the carriers supported independently of the yarn carriers and having yarn receiving notches between the teeth for the free passage of the yarn, and a driver frame for advancing the drivers and provided with pinions for positively rotating the drivers at a peripheral speed equal to the movement of translation of the outer yarn supplies relative to the inner carriers.

4. In a high speed braiding machine, the combination of a main rotary frame supporting outer yarn supplies and having an upstanding wall in which an annular groove is formed, a series of inner yarn carriers supported in a horizontal plane for free movement about the axis of the machine and having projections at their outer ends that extend into said groove to support the outer end of the carriers, supporting rollers at the inner end of the carriers which rest upon a

- run-way, means for revolving the main frame in one direction, a driver frame that is driven in the opposite direction, notched rolls at the outer end of the carriers, toothed drivers mounted upon the driver frame in position to engage the notched rolls and push the carriers around their path of travel and having deep notches between the teeth for the free passage of the yarn, and pinions secured to the drivers and operated positively to rotate the drivers at a peripheral speed equal to the movement of translation of the outer yarn supplies relative to the inner carriers.
15. 5. In a high speed braiding machine, the combination of a main rotary frame supporting outer yarn supplies and having an upstanding wall in which an annular groove is formed, a series of radially extending inner yarn carriers supported at their outer ends by projections extending into said groove and supported at their inner ends independent of said main frame, rolls upon the yarn carriers, a series of drivers that engage the rolls to traverse the yarn carriers over their path of travel and having outwardly extending teeth, the ends of which abut against said rolls to push them forward and deep notches between the teeth for the free passage of the yarn, means for positively rotating the drivers, and means for revolving the main frame in one direction and the drivers in the opposite direction.
20. 6. In a braiding machine, the combination of a main rotary frame supporting outer yarn supplies, a series of horizontal inner yarn carriers supported at their opposite ends and constructed to support yarn supplies with their axes extending toward the braiding point, a driver engaging roll upon each carrier and having a toothed periphery, a series of traveling drivers for the carriers that move about the axis of the braiding machine relative to the support for the carriers and each having a series of teeth of greater depth than the teeth of said rolls and forming spaces for the unobstructed passage of yarn, and means for revolving the main frame in one direction and the drivers in the opposite direction.
25. 7. In a high speed braiding machine, the combination of a fixed supporting frame having an annular ball raceway of large diameter for supporting a large driver gear at a substantial distance from its axis of rotation, a main rotary frame that supports the outer yarn carriers and having an annular ball raceway spaced above and of approximately the same diameter as the raceway of the fixed frame, a driver gear of large diameter rotatably mounted between said raceways to support the main rotary frame and having a raceway formed at its lower face to cooperate with the raceway of the fixed base and a raceway at its upper
30. 8. In a braiding machine, the combination of a fixed supporting frame having an annular ball raceway of large circumference for supporting a large driver gear at a substantial distance from its axis of rotation, a main rotary frame that supports the outer yarn carriers and having an annular ball raceway spaced above and of approximately the same circumference as the raceway of the fixed frame, a driver gear of large diameter rotatably mounted between said raceways to support the main rotary frame and having a raceway formed at its lower face to cooperate with the raceway of the fixed base and a raceway at its upper
35. 9. In a braiding machine of the class described, the combination of the main rotary frame carrying outer yarn supplies and having an annular trackway, a series of yarn carriers traveling in the annular trackway, positively driven rotating drivers for the carriers, outer yarn shifters pivotally mounted on the main rotary frame with a yarn guide at one side of the pivotal mounting and a shifter shoe at the opposite side thereof, bearing blocks mounted on the main rotary frame at each side of the pivot of the yarn shifters, and a cam engaged by the shoes for rocking the shifters during the revolution of the main rotary frame.
40. 10. In a braiding machine, the combination of a main rotary frame having an annular trackway and carrying outer yarn supplies, a series of inner yarn carriers, drivers for traversing the carriers in the trackway, outer yarn shifters pivotally mounted between their ends on the main rotary frame and each having an outer yarn guide at one side of its pivotal mounting and a shoe at the

opposite side thereof, an outer yarn tension device mounted on the main rotary frame between the yarn supplies and shifters, and a cam for operating the shifters.

5 11. In a braiding machine of the class described, the combination of a main rotary frame having an annular rackway, a series 10 of inner yarn carriers traveling in said trackway, outer yarn supplies mounted on the main rotary frame with their axes disposed in the direction of movement of the main rotary frame, an outer yarn guide for each of the outer yarn supplies arranged to cause the pull of the yarn to rotate the outer 15 yarn supplies, a tension device associated with each outer yarn supply, outer yarn shifters pivotally mounted on the main revoluble frame, bearings at opposite sides of the pivot of the shifters for maintaining 20 the yarn tension as the shifters are moved, and means for oscillating the shifters during revolution of the main rotary frame.

12. In a braiding machine of the class described, the combination of a main rotary frame having wide open slots for the delivery of the outer yarn, a balanced outer 25 yarn shifter pivoted between its ends on the main rotary frame, bearing blocks on the main rotary frame at opposite sides of the pivot of the shifter against which the shifter bears, a yarn guide on the shifter at one side of its pivot, a shoe on the shifter at the opposite side of the pivot, a cam for oscillating the shifter, and a yarn 30 guide on the shifter at its pivotal axis.

13. In a braiding machine of the class described, the combination of a main rotary frame carrying outer yarn supplies and having wide open slots for the passage of the outer yarn to the braiding point, an outer 40 yarn shifter pivoted between its ends to the main rotary frame and counter-balanced to avoid any snappy action on the yarn, a yarn guide at the end of the shifter, a shoe on the shifter at the opposite side of its pivot, a stationary cam for oscillating the counter-balanced shifter, and bearing blocks on the 45

main rotary frame adjacent the ends of the shifter.

14. In a high speed braiding machine, 50 the combination of a main rotary frame, a rotary driver frame, a stationary central support about which said frames are revolved in opposite directions, a toothed rack connected to the main rotary frame, a driver gear 55 connected to the driver frame, a lower anti-friction ball race supported from the main machine frame remote from the axis of rotation, a ball groove formed in the lower face of the driver gear, anti-friction balls between the race and driver gear, an upper ball race supported by and rotatable with the driver gear in a circular arc of the same radius as the lower ball race, 60 risers extending upward from the driver gear and supporting the upper ball race, a ball groove at the under side of the main rotary frame, balls interposed between the upper ball race and groove of the main rotary frame, and means for rotating the 70 main rotary frame and driver frame in opposite directions.

15. In a braiding machine, the combination of a main rotary frame having an up-standing wall, a ring mounted upon and 75 electrically insulated from said wall and having a downwardly extending annular flange spaced from said wall to provide a protected space between it and said wall which is covered by said ring, a series of 80 yarn carriers supported within the main frame to travel about an annular raceway, means for driving the carriers, electrical stop mechanism including electrical contacts upon the carriers and controlled by the yarn 85 of the inner carriers, and sliding contacts upon the inner carriers positioned to travel in said protected space formed under the ring and to contact with an inner protected wall of the ring. 90

In testimony whereof, I have signed my name to this specification.

OTTO A. FREDERICKSON.
